(57) CLAIM

The ornamental design of a bar table base, as shown and described.

DESCRIPTION

This application is related U.S. patent application Ser. Nos. 29/434,688 and 29/434,696 which are filed concurrently herewith.

FIG. 1 is an oblique view of a bar table base showing my new design;

FIG. 2 is a side elevation view thereof;

FIG. 3 is side elevation view thereof, showing the side that is opposite the side shown in FIG. 2; and

FIG. 4 is a side elevation view thereof, showing a side that is 90° from the side shown in FIG. 2;

FIG. 5 is side elevation view thereof, showing the side that is opposite the side shown in FIG. 4; and,

FIG. 6 is a top plan view thereof.

The broken line showing of the table top is included for the purpose of illustrating environmental structure and forms no part of the claimed design.
